CLAIM

The ornamental design for a feature table, as shown and described.

DESCRIPTION

FIG. 1 is a top, perspective view of a feature table, according to some embodiments;

FIG. 2 is a bottom, perspective view thereof;

FIG. 3 is a top view thereof;

FIG. 4 is a bottom view thereof;

FIG. 5 is a front view thereof, a back view thereof being an identical, mirror image of the front view; and,

FIG. 6 is a right side view thereof, a left side view thereof being an identical, mirror image of the right side view.

The broken lines are for illustrative purposes only and form no part of the claimed design.
